(57) **CLAIM**

The ornamental design for a swivel connector, as shown and described.

DESCRIPTION

FIG. 1 is an environmental perspective view of a swivel connector;

FIG. 2 is another perspective view thereof;

FIG. 3 is a top view of FIG. 2;

FIG. 4 is a back view of FIG. 2;

FIG. 5 is a bottom view of FIG. 2;

FIG. 6 is a front view of FIG. 2;

FIG. 7 is a left-side view of FIG. 2; and,

FIG. 8 is a right-side view of FIG. 2.

The broken lines shown in FIGS. 4 and 8 illustrate portions of the swivel connector and form no part of the claimed design.

1 Claim, 4 Drawing Sheets
